ATTORNEYS.

UNITED STATES PATENT OFFICE.

JAMES J. ALLISON, OF ROCK FALLS, ILLINOIS.

CHECK-ROWER.

SPECIFICATION forming part of Letters Patent No. 269,253, dated December 19, 1882.

Application filed April 24, 1882. (No model.)

To all whom it may concern:

Be it known that I, JAMES J. ALLISON, a citizen of the United States, residing at Rock Falls, in the county of Whiteside and State of Illinois, have invented certain new and useful Improvements in Check-Rowers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention has reference to that class of check-rowers which are attached to two-horse corn-planters, and are operated by a knotted wire or rope stretched in the line of movement across the field; and my invention consists essentially in certain novel and useful devices to be actuated by such knotted rope or wire, and in turn to operate the usual mechanism for measuring the seed and dropping it from the seed-hoppers, the purpose being to plant the corn in cross or check rows for the convenience and advantage of more perfect cultivation.

In the drawings, Figure 1 is a rear elevation of a machine embodying my invention. Fig. 2 is a detail view.

As the mode of attachment and operation can be readily understood by those conversant with the art, I do not deem it necessary to show or describe the corn-planter upon which my invention is placed any further than to illustrate the mode of attachment and operation.

A is the ordinary board extending across the machine between the seed-hoppers K K, and in which the ordinary seed-dropping lever is fulcrumed.

On the board A is fastened in any suitable manner the transverse beam B, above which, by means of the short standards C C C, is supported the revolving rod D, which rod is journaled on the upper ends of the standards C.

To each end of the rod D is rigidly affixed the wheel E, which consists of six radial arms, a, cleft in the line of movement of the machine, such clefts being sufficiently wide to admit of the passage of the actuating wire or rope, but not of the knots or buttons thereon.

By means of a downward-extending brace

from the beam B a deeply-grooved pulley, F, is axled immediately below each wheel E, and in such relation thereto that part of each arm a of the wheel E, in the revolution of the latter, projects into the groove b of the pulley F. The groove b is quite deep and has slightly-convex sides to prevent the knot on the wire from wedging in the groove b.

G is a wheel rigidly attached to the rod D, and having in its outer face the zigzag groove d, there being in the entire circumference of the wheel G six points or cams, m, equaling in number the arms a of the wheel E.

H is a vertical oscillating lever having its lower end pivotally attached to the ordinary reciprocating bar, I, which is connected to and directly operates the seeding devices in the bottom of the seed-hoppers K K. The lever H is fulcrumed on the side of the beam B, and at its upper end and front side is provided with a short horizontal arm, e, which projects into and traverses the groove d of the wheel G, being furnished with a friction-roller to assist its movements.

The mode of operation of my machine is as follows: The knotted wire or rope is stretched across the field in the usual manner. The machine having been brought into position, the knotted wire or rope is then placed on the pulley F in the groove b. As the machine is moved forward the wire or rope runs on the pulley F until the knot or button on such wire or rope engages the walls of the groove b, being too large to pass. The onward revolution of the pulley F carries such knot or button upward into the cleft of one of the arms a of the wheel E, and such knot or button, engaging the said arm a in the cleft, carries the arm a toward the rear far enough to release the button or knot aforesaid. This movement of one arm a draws the next arm a into position to be engaged and actuated by the next button or knot. Each action of one arm a revolves the rod D far enough to cause the wheel G to force the arm e into the point of the next cam m, which motion, communicated through the oscillating vertical lever H to the reciprocating bar I by means of the latter, actuates the seed-slides and drops one hill from each of the seed-hoppers. When the field has been crossed the wire or rope is lifted from the pul-

ley F, and after the machine has been turned placed on the corresponding pulley F on the other end of the rod D.

What I claim as my invention, and desire to 5 secure by Letters Patent of the United States, is—

1. In a check-rower, the combination of the wheel E, having radial cleft-arms *a*, a knotted rope or wire, and the pulley F, having the 10 groove *b*, when such wheel and pulley are so located in relation to each other that the arms *a* in their revolution project into the groove *d* of the pulley F, substantially as shown, and for the purpose described.
- 15 2. The combination of the wheel E, having cleft-arms *a*, the pulley F, rod D, and wheel G, having the groove *d*, all substantially as shown, and for the purpose specified.

3. In a check-rower, the combination of the wheel E, pulley F, rod D, wheel G, and lever 20 H, adapted to be operated by a knotted rope or wire, substantially as shown, and for the purpose mentioned.

4. In a check-rower, in combination with the reciprocating bar I for actuating the seeding 25 devices, the lever H, wheel G, rod D, pulley F, wheel E, and a knotted rope or wire, substantially as shown, and for the purpose described.

In testimony whereof I affix my signature in 30 presence of two witnesses.

JAMES J. ALLISON.
